THREAD CONTROL FOR WEFT
REPLENISHING LOOMS

Richard G. Turner, Worcester, Mass., assignor to
Crompton & Knowles Loom Works, Worcester,
Mass., a corporation of Massachusetts

Application February 1, 1951, Serial No. 298,857

16 Claims. (Cl. 139—257)

1

This invention relates to thread controllers for thread holders in weft replenishing looms and it is the general object of the invention to provide means auxiliary to the thread holder effective to move the thread of a transferred bobbin toward the thread holder.

A form of thread holder which has gone into general use includes pneumatic means to draw the threads or weft ends extending from reserve bobbins in a magazine into an intake mouth and thence into a thread collector. Sub-atmospheric pressures existing within the thread collector hold the threads in the mouth taut to keep them above the reciprocating lay and these pressures are also effective when certain types of weft are used to remove the thread of a transferred bobbin when the latter is cut at the selvage of the cloth. When hairy weft yarns are used however difficulty is experienced in drawing the cut thread of a transferred bobbin into the thread collector and it is an important object of the present invention to provide an advancer for the cut thread located between the pneumatic thread holder and the magazine effective to move the thread toward the intake mouth of the thread holder.

It is a further object of the invention to provide a thread advancer in the form of a rotatable cylinder having a friction surface turning during loom operation in a direction to advance a thread in engagement therewith toward the intake mouth of the thread holder.

Hairy yarns show some tendency to stick to the friction surface of the advancer and it is a further object of the invention to provide a stripper between the rotating advancer and the thread holder effective to dislodge the threads from the advancer at a point adjacent to the intake mouth and preferably below a line extending from the top of the advancer to the intake mouth so that the advancer by its engagement with the thread will tend to draw the latter downwardly away from the group of other threads in the intake mouth leading to the untransferred bobbins.

It is a still further object of the invention to provide mechanism operating preferably during loom operation to turn the aforesaid thread advancer so that it will be effective during picks or beats of the loom subsequent to a transferring operation to move the thread of a transferred bobbin toward the thread holder as soon as this thread is cut at the selvage.

It is another object of the invention to locate the thread advancer in such position that it

2

will be below the threads extending from the untransferred bobbins in the magazine and be able to act only on the thread of a transferred bobbin.

5 With these and other objects in view which will appear as the description proceeds, the invention resides in the combination and arrangement of parts hereinafter described and set forth.

10 In the accompanying drawings, wherein two forms of the invention are set forth,

Fig. 1 is a side elevation of part of a loom having the preferred form of the invention applied thereto.

15 Fig. 2 is an enlarged plan view looking in the direction of arrow 2, Fig. 1.

Fig. 3 is an enlarged vertical section on line 3—3, Fig. 2.

20 Fig. 4 is an enlarged detail view looking in the direction of arrow 4, Fig. 1, parts being in section.

Fig. 5 is an enlarged end view looking in the direction of arrow 5, Fig. 2, showing the advancer and associated parts of the thread holder.

25 Fig. 6 is a detail vertical section on line 6—6, Fig. 5.

Fig. 7 is a diagrammatic view showing the relation of the advancer to a reserve bobbin magazine, the lay of the loom and pneumatic thread holder for both forms of the invention.

30 Fig. 8 is a plan view of part of the loom having the modified form of the invention applied thereto, and

Fig. 9 is an enlarged vertical section on line 9—9, Fig. 8.

35 Referring particularly to Fig. 1, the loom frame 1 supports a lay 2 which is reciprocated backwardly and forwardly by means of a top or crank shaft 3 and connectors 4. The lay has a shuttle box 5 to receive a shuttle 6 which may be one of several shuttles when the loom is of the multicolor type.

40 The loom frame supports a magazine M which in the present instance is of the multicolor type and stores reserve untransferred bobbins in four groups designated herein at B1, B2, B3 and B4. Weft ends or threads W extend from these bobbins to a thread holder designated generally at H.

45 The holder in the present instance is of the pneumatic type and includes a head 10 supported by a hollow cylinder 11 the lower end of which is connected to a hose 12 leading to an air pump 13 mounted on the loom frame. The air pump 13 has a piston 14 reciprocating in a cylinder 15

and operated by a lever 16 connected to the lay rod 17. During backward movement of the lay, or to the right as viewed in Fig. 1, the pump 13 creates subatmospheric pressures within the cylinder 11.

The thread holder has a walled structure designated at 20 extending upwardly from the head 10 and having the interior thereof in communication with the interior of the cylinder 11 by means of an opening 21 in the head 10. A cover 22 extends across the top of the wall structure 20 and is hinged to the latter as at 23. The cover and that part of the wall structure adjacent to the magazine define a thread intake mouth 24. The weft ends W extend into this intake mouth and through the thread holder and opening 21 into the cylinder 11. By reason of the subatmospheric pressures created within the cylinder the weft ends W are held taut above the back and forth path of the reciprocating lay.

At the time of a weft replenishing operation one of the reserve bobbins from the magazine will be pushed into a shuttle in shuttle box 5 by a transfer arm 25 operating in usual manner. At this time the weft end or thread T corresponding to the transferred bobbin will descend to a position below the threads W of the untransferred bobbins. The replenished shuttle is then picked across the loom, or to the left as viewed in Fig. 7, and subsequently cutter mechanism designated generally at C will cut the thread T at a point spaced from the thread holder and preferably adjacent to the selvage. The cut thread falls from the point of cutting but because it still extends into intake mouth 24 it is subject to pneumatic traction. If the thread is of the smooth type it can be drawn into the cylinder 11, but if the thread is of a coarse hairy type it may be so entangled with the other threads extending into the intake mouth that it cannot readily be drawn into the cylinder 11. When the thread T is cut by the cutter mechanism C it falls away from the cloth or fabric F and hangs from the thread holder.

The matter thus far described may be similar to the thread holder set forth in my prior Patent No. 2,476,640 to which reference may be had for a more complete description of the structure and operation of the thread holder.

In carrying the preferred form of the present invention into effect a base plate 30 is secured to head 10 by screws 31 and has upright bearings 32 and 33 secured thereto as at 34 and 35, respectively. Rotatable in these bearings is a shaft 36 to which a thread advancer 37 is secured as by set screws 38. The advancer is shown herein as being in the form of a cylinder to the outer periphery of which is secured, as by cementing, a layer 39 of friction material, such as felt.

The right end of shaft 36 as shown in Fig. 3 has a reduced extension 40 on which is driven a ratchet wheel 41 which turns with the shaft and the advancer. A lever 42 is rockable on the shaft extension 40 and has an arm 43 to which is secured a stud 44. A pawl 45 is pivoted on the stud and is held yieldingly against the ratchet wheel by a spring 46 one end of which is connected as at 47 to the pawl and the other end of which extends outwardly through a slot 48 in a drum 49 secured in angularly adjusted position on the stud 44 by set screw 50.

Lever 42 has a second arm 51 operatively connected to a rod head 52 secured to the upper

end of a rod 53. The rod head has a hole 54 therethrough to receive the lever arm 51, and a washer 55 and cotter pin 56 hold the head to the lever arm 51.

The lower end of rod 53 is pivoted as at 57 to an arm 58 secured to the rocker iron 59 of the loom. This rocker iron is secured to the usual rocker shaft RS which supports and rocks with the lay 2. As the lay reciprocates the arm 58 rises and falls to effect vertical reciprocation of rod 53.

The screws 31, in addition to holding the base plate 30 in position with respect to head 19, also affords means for securing a stripper 60 and a guard 61 to the head. The stripper extends upwardly from plate 30 as shown in Fig. 5 and has an edge 62 which lies against the friction material 39 and engages the latter at a point below the line extending from the top of the rotary 15 advance 37 to the mouth 24 of the thread holder. 20

The guard has two arms 65 and 66 which extend upwardly and over the bearings 32 and 33, see Figs. 3 and 5. The purpose of the guards is to prevent thread T from passing down between either end of the advancer 37 and the adjacent bearing.

In the operation of the preferred form of the invention the rising and falling of rod 53 will cause the pawl 45 to advance the ratchet wheel with a step-by-step movement and turn the upper part of the thread advancer 37 toward the thread holder. Retrograde movement of the advancer is prevented by a hold pawl 68 also held in position by the screws 31 and engaging the ratchet wheel. The advancer 37 is preferably low enough so that it will have little or no contact with the thread T prior to cutting of the latter at the selvage. This relation is desirable but not essential. When thread T is eventually cut by the cutter mechanism C as already described it will fall from the full line to the dotted line position shown in Fig. 7 and will rest on the advancer. As the latter is turned incident to loom operation the friction surface 39 will move the thread T upwardly and advance it toward the intake mouth 24. The stripper will prevent the thread from clinging to the surface 39 and release the thread so that it can fall into the space between the advancer 37 and the thread holder. Subatmospheric pressures within the thread holder will tend to draw that part of the thread between the advancer and the holder into the latter, and eventually the entire thread will be moved upwardly and to a position where it can be sucked into the intake mouth 24.

In the modified form of the invention shown more particularly in Figs. 8 and 9 the loom frame 70 has secured thereto a laterally extending frame 71 carrying a bearing 72 for a top or crank shaft 73 similar to shaft 3 described in connection with the preferred form of the invention. Secured to the shaft 73 as at 75 is a flat friction plate or disk 76 having engagement with a friction roller 77 mounted for rotation on a stand 18 secured to the frame 71. This roller is secured to the core 80 of a flexible shaft designated generally at 81 and having a sheath 82 the right end of which as viewed in Fig. 8 is secured as at 83 to the stand 78.

The flexible shaft 81 extends forwardly and has its left end, Fig. 8, secured to a stand 85 fixed to the base plate 30. The core of the flexible shaft extends into and is secured to a shaft 87 similar to shaft 36 and having secured thereto

a thread advancer 88 which is similar to the advancer 37. The bearings for shaft 87 and the manner of holding the advancer 88 to the shaft 87, as well as the thread guards and stripper, may be the same as similar parts described in connection with Fig. 3.

The roller 77 may have a friction surface provided for instance by rubber or similar material so that it will be rotated by frictional contact with the disk 76 as the top shaft 73 rotates incident to loom operation, and the core of the flexible shaft will cause the advancer 88 to rotate continuously as the loom operates and in the same direction as does roller 37.

In this modified form of the invention it may be possible to cause several rotations of the advancer roll or member 88 for each pick of the loom or rotation of the shaft 73, depending upon the diameter of the roller 77 and the distance between its point of contact with the disk 76 and the center of shaft 73. Except for the manner of driving the advancer 88 the modified form of the invention operates in a manner similar to that described for the preferred form.

From the foregoing it will be seen that the invention sets forth simple means by which the cut thread of a transferred bobbin in a weft replenishing loom can fall across a thread advancer which moves in such direction as to advance the thread toward the intake mouth of a pneumatic thread holder. In the preferred form of the invention the advancer is a rotary member 37 rotated intermittently with a step by step motion produced by the pawl and ratchet mechanism shown more particularly in Fig. 5, whereas in the modified form of the invention the rotary advancer 88 is rotated continuously by connection with some part of the loom. It will not be necessary in all instances, however, to have the advancers moved by the specific mechanisms shown herein. The stripper 60 prevents the thread T from being wrapped around the advancer and enables the latter to move the thread T toward the thread holder. The stripper preferably engages the periphery of the advancer at a point low enough to enable the rotating advancer to effect some downward motion of the thread toward the thread holder before stripping occurs. The guards 61 prevent the thread from falling on the bearings for the advancer. In both forms of the invention the advancer engages only the thread of the transferred bobbin without engaging the other threads, and is therefore able to move this thread independently of the threads connected to the untransferred bobbins in the magazine.

Having thus described the invention it will be seen that changes and modifications of the foregoing specific disclosure may be made without departing from the spirit and scope of the invention.

What is claimed as new is:

1. In thread controlling means for a loom having a group of threads extending from reserve bobbins in a magazine and wherein the thread of a transferred bobbin is cut, a pneumatic thread holder into which the threads are drawn due to subatmospheric pressures existing within the holder, a thread advancer adjacent to the thread holder on which the cut thread of the transferred bobbin falls, and means moving the advancer in a direction to move said thread toward said thread holder.

2. The thread controlling means set forth in claim 1 wherein the thread advancer is a rotary

member having a friction surface the upper part of which turns toward the thread holder.

3. The thread controlling means set forth in claim 1 wherein a thread collector is associated with the thread holder and supports the thread advancer.

10 4. The thread controlling means set forth in claim 1 wherein the thread advancer is a rotary member having a friction surface and a stripper between the advancer and thread holder strips the thread from the advancer.

15 5. The thread controlling means set forth in claim 1 wherein the thread advancer is below and out of engagement with the group of threads extending from the bobbins in the magazine.

20 6. The thread controlling means set forth in claim 1 wherein the thread advancer is a rotary member and said means includes a ratchet wheel fixed with respect to the rotary member and a loom operated pawl.

25 7. The thread controlling means set forth in claim 1 wherein the thread advancer is a rotary member and the loom has a lay and the means includes a pawl and ratchet mechanism operated by the lay.

30 8. In thread controlling means for a loom having threads extending from reserve bobbins in a magazine and wherein the thread of a transferred bobbin is cut from the cloth being woven, a pneumatic thread holder into which the threads are drawn due to subatmospheric pressures existing within the holder, a cylindrical thread advancer on which the thread of the transferred bobbin falls when cut, bearings on the thread holder in which the advancer is rotatably mounted, and means rotating the advancer in a direction to move a thread resting thereon toward said thread holder.

35 9. The thread controller set forth in claim 8 40 wherein guard means overhangs said bearings to prevent the thread of the transferred bobbin from falling onto said bearings.

45 10. In thread controlling means for a loom having a group of threads extending from reserve bobbins into the intake mouth of a pneumatic thread holder within which subatmospheric pressures exist and wherein the thread of a transferred bobbin is cut from the cloth being woven, a thread advancer rotating during loom operation under said thread and on which the latter falls when cut, the top of said advancer turning toward said thread holder.

50 11. The thread controlling means set forth in claim 10 wherein a stripper between the thread holder and the advancer engages the latter below a line leading from the top of the advancer to the intake mouth of the thread holder.

55 12. In thread control means for a loom having threads extending from reserve bobbins in a magazine and wherein the thread of a transferred bobbin is cut and falls from the cloth being woven, a pneumatic thread holder into which said threads are drawn by subatmospheric pressures existing within the holder, a thread advancer between the magazine and thread holder mounted for rotation and on which the cut thread falls, and means continuously rotating said advancer during loom operation in a direction to move said thread toward said thread holder.

60 13. In thread control means for a loom having a part which rotates continuously during loom operation and having also a group of threads extending from reserve bobbins in a magazine into the intake mouth of a pneumatic thread holder and wherein the thread of a transferred bobbin

is cut, a rotatable thread advancer adjacent to the thread holder on which the cut thread falls, and means operatively connected to said part of the loom continuously rotating said advancer during loom operation in a direction to move said thread toward said thread holder.

14. The structure set forth in claim 12 wherein said means includes a friction disk secured to said part of the loom and a friction roller engaging the disk and operatively connected to said advancer.

15. The structure set forth in claim 12 wherein said part of the loom is a shaft having a friction disk secured thereto and said means includes a roller engaging the disk and rotated thereby and a flexible shaft operatively connecting the roller and advancer.

16. In thread controlling means for a loom having a group of threads extending from reserve bobbins in a magazine into a pneumatic thread holder within which subatmospheric pres-

10

sures exist and wherein the thread of a transferred bobbin while extending into the thread holder is cut at a point spaced from the latter and falls, a thread advancer located between said thread holder and said point under the thread of the transferred bobbin and onto which the thread falls when cut at said point, and means operative to move the advancer in a direction to cause the latter to advance said thread toward the thread holder.

RICHARD G. TURNER.
